UNITED STATES PATENT OFFICE

157,461

BLOUSE

Marsh Adler, Los Angeles, Calif., assignor to Deauville Models, Inc., Los Angeles, Calif., a corporation of California

Application August 23, 1948, Serial No. 148,258

Term of patent 3½ years

(Cl. D3—25)

To all whom it may concern:

Be it known that I, Marsh Adler, a citizen of the United States, residing at Los Angeles, in the county of Los Angeles and State of California, have invented a new, original, and ornamental Design for a Blouse, of which the following is a specification, reference being had to the accompanying drawing, forming part thereof.

Fig. 1 is a front view of a blouse showing my new design.

Fig. 2 is a rear view of the same.

I claim:

The ornamental design for a blouse, as shown.

MARSH ADLER.
